Carpet Pattern.

ELEMIR J. NEY, OF LOWELL, MASSACHUSETTS,

ASSIGNOR TO THE LOWELL MANUFACTURING COMPANY.

Letters Patent for a Design No. 84, dated July 16, 1861.

SPECIFICATION.

TO ALL WHOM IT MAY CONCERN:

Be it known, that I, ELEMIR J. NEY, of Lowell, in the county of Middlesex and State of Massachusetts, have originated and designed a new Pattern for Carpets or other fabrics; of which the following is a full, clear, and exact description, reference being had to the accompanying drawings making part of this specification.

Corner A is one-fourth a figure composed of eight leaves, arranged about an eight-pointed figure, and surrounded by a band of sprigs resting on the ground B. The frame 1 surrounds the ground B, and is itself surrounded by a series of small balls and a wreath of sprigs, connected at their stems by a scalloped band.

Corner C is one-fourth of an eight-pointed set figure, surrounded by the frame 2. Around the frame 2 is a band 3, consisting of small balls, diminishing in size from the inside to the outside edge. Fig. D D is a broad belt or ribbon, which is partially covered by the group of flowers E. Small leaves surround the belt D D and group E, and occupy the space between said figures and the band 3. F, at the side, is a group of leaves and flowers resting on the indented ground 4.

The colors employed for the different portions of the design may be varied to suit the taste and wish of the manufacturer.

Claim.

What I claim as my invention, and desire to secure by Letters Patent, is—
The design or pattern for carpets or other fabrics herein set forth.
